UNITED STATES PATENT OFFICE.

LESLIE H. GALE, OF WORCESTER, MASSACHUSETTS.

ROUTING MACHINE.

Application filed October 12, 1921. Serial No. 507,260.

To all whom it may concern:

Be it known that I, LESLIE H. GALE, a citizen of the United States, residing at Worcester, in the county of Worcester and State of Massachusetts, have invented a new and useful Routing Machine, of which the following is a specification.

This invention relates to a machine for routing printing plates.

The principal objects of the invention are to provide a machine which will rout either curved or flat plates without reorganization of the machine and with the employment of a very simple adjustment; to provide an improved arrangement for lifting the routing head; to provide improved driving means and adjustments therefor for operating the routing tool and an improved tool head; and generally to provide a simple and practical machine capable of performing all the operations necessary in routing either curved or flat plates.

The invention also involves improvements in various details of construction of the machine.

Reference is to be had to the accompanying drawings, in which

Fig. 1 is a side view of a routing machine constructed in accordance with this invention;

Fig. 2 is a plan of the same;

Fig. 3 is a rear elevation with parts in section;

Fig. 4 is a front elevation of the table showing the plate-holder;

Fig. 5 is an end view of the front portion of the table showing the plate-holder in the same position, that is, the position for routing a flat plate;

Fig. 6 is a similar view of the same in section showing the parts in position for routing a curved plate;

Fig. 7 is a side elevation on enlarged scale showing the routing tool support and driving devices, and

Fig. 8 is an elevation on enlarged scale of the routing head.

In order to provide routing mechanism located at the proper elevation and in convenient position for operation I prefer to employ a cast metal base 10 adapted to rest on the floor and supporting a routing table

11. This table is provided with a series of holes or depressions 12 for the reception of stops for holding the edge of a flat plate, and 55 is also provided with a recess 13 in which is journalled a plate support 14. This support has a flat top 15 provided with a dovetail groove 16 for a plate clamp 17 of any desired character. When a flat plate is to 60 be routed it rests partly on this support and partly on the table 11 with which the flat top of the support 14 is flush. The support is also provided with a projecting portion, preferably of curved form, for supporting a semi-circular or other curved plate, and this has grooves 18 for plate clamps. These grooves are so located as to receive curved plates of different diameters to be clamped on the support. 70

The plate support 14 is mounted on a shaft 20. This shaft is provided with a gear 21 operated by a worm 22 on a shaft 23. A hand wheel 24 on the shaft is employed for turning the gear and shaft so as 75 to turn the plate-holder from the position shown in Fig. 5, for example, to that shown in Fig. 6.

The shaft 20 is mounted in a pair of brackets 26 carried by the table. A bracket 80 25 supports the shaft 23 also.

On the rear of the table is a vertical pivot pin 30 on which is pivoted a bracket 31 adapted to swing about the axis of the pivot, but ordinarily clamped firmly in the position indicated. This bracket has an upward extension 32 provided with a horizontal stud or shaft 33 to which is fixed a guide 34 having a dove-tailed groove across it for the reception of a slide 35. This slide is 90 not fixed in position, but is capable of moving out and in at will, and is also capable of swinging up and down about the stud 33 freely.

On the end of this slide there is a vertically slidable head 36 which carries a hollow shaft 37 that supports the routing tool 38 below. This routing tool is driven by a belt 40 from a motor located on the machine or from a countershaft as desired and operating on a pulley 41. This pulley is slidably keyed to a shaft 42 which is journalled in a U-shaped bracket 43 pivoted on the horizontal stud 33. The shaft 42 passes into

the head 36 and has a bevel gear 44 which drives a bevel gear 45 slidely keyed on the hollow shaft 37 and meshing with it. The shaft 37 runs in upper and lower ball 5 bearings 46. Behind the gear 45 is a spring 47 holding the bevel gears in mesh and the shaft 37 in operative connection with the power. By means of a head 48 on its upper end an inner tool clamping rod 49 in the shaft 37 can be operated to open and close the jaws that hold the routing tool. The rod 49 is threaded at the top and the head is turned to raise or lower the rod.

On the head there is an arm 56 having a handle or wheel 57 which the operator holds in his right hand to steer the mechanism and on the other side is a handle 58 which passes under his left arm to help him guide it.

20 The slide 35 is held by a bar 50 normally resting on a pair of studs 51. With this bar is connected a link 53 pivoted to a lever 54 swinging on a horizontal axis on the frame. With the other end of the lever is connected a flexible connection 55, for example a cable, which passes through a notched or slotted plate 66 on the bottom of the frame. This cable is connected with a foot lever 67 pivoted on a horizontal axis at the bottom. When the operator desires to raise the routing tool he steps on the outer end of the lever 67 which pulls the cable down and raises the bar 50. This raises the routing head and brings the tool up out of contact with the work.

It will be seen that a single machine is adapted to rout flat or curved plates of any standard curvature, thus substantially halving the cost of this equipment for a small plant. The adjustment from one use to the other is extremely simple and does not require any special skill. The routing head is of good mechanical construction and easily manufactured as above specified.

45 Although I have illustrated and described only one form of my invention, I am aware of the fact that changes and modifications can be made therein by those skilled in the art without departing from the scope thereof as expressed in the claims.

Therefore, I do not wish to be limited to all the details of construction herein shown and described, but what I do claim is:—

55 1. In a routing machine, the combination with a flat routing table, of a plate support mounted to turn adjacent thereto and having a flat top adapted to be turned into position flush with said table, said support having a projecting portion adapted to be turned into a position to support a curved plate near said table.

60 2. In a routing machine, the combination with a flat routing table having a recess therein, of a plate support mounted to turn adjacent thereto and having a flat top

adapted to be turned into position in said recess flush with said table, said support having a projecting portion adapted to be turned into a position in said recess to support a curved plate.

70 3. In a routing machine, the combination with a routing table, of a horizontal shaft supported thereby below the table, and a plate support rotatable on said shaft and having a plurality of surfaces arranged and 75 adapted to carry different kinds of plates with their upper surfaces above the plane of said table.

4. In a routing machine the combination with a routing head adapted to carry a rotary routing tool, of a plate support having surfaces for carrying a flat plate and a curved plate adjacent to said head, said head having a routing tool shaft, a spring on the routing tool shaft for keeping it in 85 operative connection with the power, and means for lifting said routing tool shaft irrespective of the action of the spring.

5. In a routing machine, the combination with a routing head, of a support adapted 90 to move to two positions, in one of which it is capable of supporting a flat plate under the head and in the other of which it will hold a curved plate in substantially the same position, said head having a routing tool shaft, a gear for driving it, a spring for holding the gear in operative position, means for lifting said routing tool shaft in spite of the action of the spring, and means on the head for driving the gear whenever 100 the spring is in action.

6. In a routing machine, the combination with a routing head, of a support capable of supporting a plate under the head, a base on which said support is mounted, a slide pivoted on a horizontal axis on which said head is mounted, a foot pedal at the bottom of the base, and means whereby the depression of the pedal will raise said slide and head about the horizontal pivot.

110 7. In a routing machine, the combination with a routing head, of a support capable of supporting a plate under the head, said head having a routing tool shaft, a gear slidably keyed thereon, a spring for holding the gear in operative position, means for lifting said routing tool shaft, and means on the head for driving the gear whenever the spring is in action.

115 8. In a routing machine, the combination with a routing head, of a support capable of supporting a plate under the head, a base on which said support is mounted, a slide pivoted on a horizontal axis on which said head is mounted, a foot pedal at the bottom of the base, and means whereby the depression of the pedal will raise said slide and head about the horizontal pivot.

120 9. In a routing machine, the combination with a plate supporting table, of a bracket

pivoted thereon on a vertical axis, a horizontal stud on said bracket, a bracket pivoted on said stud and having a pair of bearings, a shaft slidably mounted in said bearings and adapted to swing about said stud, means for driving said shaft, a guide also pivoted on said stud, a slide movable along

the guide, a routing head carried by said slide, and means on said shaft for operating the routing head.

10

In testimony whereof I have hereunto affixed my signature.

LESLIE H. GALE.
